UNITED STATES PATENT OFFICE

PERCY E. BARKER, OF CLEVELAND, OHIO, ASSIGNOR, BY MESNE ASSIGNMENTS, TO THE CINDERELLA WASHING MACHINE COMPANY, OF CLEVELAND, OHIO, A CORPORATION OF OHIO

WASHING MACHINE

Application filed October 19, 1927. Serial No. 227,188.

My invention relates to washing machines, and the invention is an improvement in the class of washing machines in which a washing liquid is agitated by a motor-driven fan. 5 As an exemplification of one type of washing machine in that class, reference may be had to my own United States Patent No. 1,624,461, dated April 12, 1927. The operation of the present machine is in some respects similar 10 to my patented device but the structure has been modified to meet different conditions and to be of general utility in washing a variety of articles requiring that service frequently in the average home. To explain, various 15 motor-driven appliances are commonly used in households of today, including machines for washing clothes, dishes, etc. The clothes washing machines in general use are of sufficient size and capacity to hold a large 20 amount of water and a large batch of goods and to operate satisfactorily on sheets and other articles of large dimensions. However, a housewife has constant occasion to wash 25 small quantities of goods and sundry articles in daily use, such as towels, silk and linen stockings, diapers, handkerchiefs, lingerie, garments of fine materials, etc. To meet that need I have devised a small machine for washing individual pieces or small batches of goods 30 such as mentioned, and have so constructed the device that it may be placed upon a stove and the water heated while the motor is in 35 operation without damage or ill effect to the operating parts. Moreover, I provide the liquid receptacle with handles or a swinging 40 bail to permit the same to be easily transported, either with or without the operating mechanism, which is particularly arranged 45 and mounted to permit its free removal from the liquid receptacle and to permit it to be 50 handled as an independent unit. As constructed this operating unit is used in part as a cover and in part as a cylinder to provide a washing chamber for the goods and in combination with the liquid receptacle, to provide air chambers and passages in certain desired relations to effect agitation of the liquid and goods with efficient washing results when the goods and a certain amount of cleansing 55 solution is placed within the liquid receptacle,

all substantially as hereinafter shown and described in greater detail.

In the accompanying drawings, Fig. 1 is a perspective view of my improved washing machine as it may be actually used if desired. 55 Figs. 2 and 3 are sectional views, horizontally and vertically of the machine on line 2—2 of Fig. 3 and line 3—3 of Fig. 2 respectively. Fig. 4 is a side elevation of the operating unit or inner cylinder, also hereinafter referred to as "cylindrical skirting" or "inner tank" or "inner receptacle" as will be plainly understood from the context, and Fig. 5 a side elevation of the pail or liquid receptacle, also hereinafter referred to as "outer cylindrical member" or "outer cylinder" or "outer tank," as also will be plainly understood, a portion being in section to show the interior in each figure. Fig. 6, Sheet 1, is a sectional view of a modification. 60

The invention comprises a cylindrical receptacle or vessel A made of any suitable material, preferably tin, copper, or other non-corrosive sheet metal. The size of this receptacle may vary considerably but in making 65 a portable machine for rapid washing of individual pieces or small batches of goods I find it desirable to make the receptacle about thirteen inches in diameter and twelve inches in height. A swinging bail or ached handle 70 75 80 85 90 95 100 2 may be attached to receptacle A to permit it to be carried and handled conveniently, and an overflow opening 3 is provided at one side of the receptacle, which opening may be closed by a cork or bung 4, or other device, when occasion requires. Incidentally the machine will operate with lesser or greater amounts of water, but with an overflow opening 3 located at a predetermined elevation it follows that the receptacle can only be filled to that level thereby assuring maximum efficiency in operation. Opening 3 may be open or closed in washing operations, but having the bung in place initially the receptacle may be filled to any height and then emptied to the desired level without error or calculation by simply removing the bung. A circular drain opening and bung, Figure 6, may be used at or near the closed bottom of the re-

ceptacle, if desired, to facilitate quick and complete discharge of the water.

The operating mechanism or inner working unit B used with receptacle A to effect agitation of the water and washing of the goods is entirely independent of the receptacle and may be removed therefrom bodily. However, as constructed, unit B comprises a flanged top or cover 5 which is adapted to 10 rest loosely upon the border rim or bead 6 of receptacle A and from which top or cover a hollow cylinder or cylindrical wall forming an annular skirting 7 is suspended so that it may be sleeved concentrically in spaced relation to cylindrical wall 8 of receptacle A. Thus cylinder 7 is of slightly smaller diameter than receptacle A to provide an annular space or chamber 9 extending downwardly to the bottom of the outer receptacle or cylindrical member A, although the bottom edge 10 of cylinder 7 is preferably not in close contact with the bottom but spaced uniformly apart therefrom, say about one-half an inch when cover 5 is resting unevenly or loosely 20 upon border rim 6, which may be irregular or provided with raised seats at one or more places therein, or the cover may be so formed as to provide an air passage or space which will permit free communication between the 25 upper end of the annular space or chamber 9 and the outer atmosphere. Immediately beneath cover 5 and spaced apart therefrom is a dished transverse diaphragm 11 fixed at its periphery or flanged edge 12 to cylinder 7 30 which contains one or more slots or lowered openings 13 radially thereof to provide connecting air passages and free fluid flow between the annular space or chamber 9 and the upper compartment or chamber 14 formed in the cylinder 7 by cover 5, the upper portion 35 of skirting 7 and diaphragm 11. A raised central portion in diaphragm 11 contains a circular opening 15, and a dished baffle plate or guard member 16 is secured by rivets or bolts 17 in a spaced position to the bottom face of diaphragm 11 opposite opening 15. From the foregoing it will be seen that annular chamber 9, upper chamber 14, and a central washing chamber 18, which is formed 40 within the inner cylinder 7 below the diaphragm 11, are in open communication at all times when the working unit 3 is sleeved within the outer receptacle A, and that an annular space 19 is also provided beneath the bottom edge 10 of cylinder 7 which in the absence 45 of water from receptacle A will afford free liquid flow between outer chamber 9 and central chamber 18 annularly at their bottoms. When liquid receptacle A is filled with water 50 to approximately the level of overflow opening 3 the annular passage 19 at the base of chambers 9 and 18 is obviously throttled or closed, and the body of water in the large central washing chamber 18 is level with the 55 water in the annular space 9. Upon exhaust-

ing the air rapidly in the upper part of washing chamber 18 the water in chamber 18 rises and the water in annular space 9 is lowered by atmospheric pressure until the water level in space 9 is level or substantially 60 level with the bottom edge 10, whereupon the water seal for chamber 18 will be broken and air will rush upwardly thereto and cause the water to surge back into annular space 9 notwithstanding the rapid revolutions of a 65 suction fan 20 seated in the upper chamber 14 adjacently above the opening 15 in diaphragm 11. Fan 20 is mounted upon the shaft of an electric motor 21 secured in a 70 vertical position centrally within and upon cover 5 by a detachable clamping collar 22, the fan being free to rotate centrally within air chamber 14, and the electric motor being protected from the water by its own casing, and the baffle member 16. Detachment of 75 clamping collar 22 permits the motor and fan to be removed bodily from top or cover 5, and a rubber or leather sealing ring and cushioning gasket 23 may be employed with the clamping collar to fasten the motor in sealing 80 connection with said top or cover. 85

To operate the machine, the working unit B is first removed from liquid receptacle A and the latter filled to the desired level with water and suitable cleansing agents, such as 90 soap. The articles to be washed are then deposited in the water, and unit B placed upon and within receptacle A, the cylinder 7 bearing down upon the goods and resting thereon when gathered at the bottom of the receptacle. In such case the top or cover may be spaced more or less above and apart from rim 95 6 of receptacle A due to the accumulation of clothes under the bottom edge 10 of the depending cylindrical skirt 7. Upon switching 100 on the electric current and starting the motor the air is rapidly exhausted from chamber 18, and the goods underneath edge 10 of cylinder 7 will be drawn immediately into the washing chamber 18 which permits the entire 105 unit to settle until cover 5 is seated upon border rim 6. Assuming water is present to the depth of seven inches the motor will start at normal speed and as the air is exhausted and the air pressure reduced around the fan, the motor will pick up or increase its speed 110 correspondingly. When the pressure within the washing chamber 18 is approximately a quarter of a pound lower than atmosphere 115 pressure the water inside of the washing chamber is at a higher elevation and the water in annular space 9 has been lowered to approximately the same level as the annular bottom edge or rim 10 of the skirting or cylindrical wall 7. Then the water seal 120 will be broken and air will rush suddenly in volume around the annular bottom edge 10 into the inner working chamber 18 and upwardly in a ringlike area adjacent the circular wall 7. A substantial amount of air is 125 130

drawn in suddenly in that way, which crowds or forces the body of water toward the center with agitating effect. The inrush of air places an additional load on the constantly revolving fan and decreases its speed, and the pressure inside and outside is momentarily equalized, which permits the water to drop instantly within the washing chamber 18 and rise rapidly in the outer space or chamber 9. The goods in the water may at times restrict the free passage of the air to some extent and agitation of the goods and water brought about irregularly and intermittently. The rapid changes in pressure by the sudden breaking of the water seal causes agitation and regurgitation of the water and the goods to such an appreciable extent that the goods will be thoroughly washed in about fifteen minutes, more or less, dependent upon the cleansing agent in use and whether hot or boiling water is employed. The suction fan 20 runs continuously at varying speeds. To expedite washing operations, the water may be constantly heated while the motor is operating, inasmuch as the receptacle is relatively small and portable and may be readily placed upon a stove, say above a gas burner in a gas stove. When the washing operation is completed, a rinsing operation may be performed in the same receptacle and with the same operating unit. Or, a duplicate liquid receptacle or outer tank may be used for rinsing purposes, using the same operating unit or inner tank and shifting the latter from one outer receptacle to the other.

To illustrate a few minor modifications which might be made, reference may be had to Fig. 6, in which the outer liquid receptacle A' and inner operating unit B' are in the main the same as in the structure hereinbefore described, but differing therefrom in the following respects. Thus, the cylinder or skirt 7' forming the depending part of unit B' is shown as corrugated annularly in the lower area or zone which provides the washing chamber 18'. Obviously the corrugated surface provides a rubbing surface for the agitated goods as the water rises and falls within the chamber. The baffle member 16' in this device is also formed with a notched flange 16" extending upwardly in engagement with diaphragm 11' to prevent the goods or a light or small piece of material from being drawn into the opening 15' and the fan. The border edge of the top or cover 5' is also provided in this case with downwardly stamped projections 24 to seat the top cover in slightly spaced position upon the rim of the outer liquid receptacle A'. As an alternative the cylindrical skirting 7' may rest on a corrugated bottom, ribs or raised seats 25 on bottom 26 of receptacle A'.

The slight air space or passage which is provided at the seating rim for the cover prevents the building up of pressure beyond

atmospheric pressure within the fan chamber, and consequently there is no leakage of steam or water from this chamber to the motor casing. A recirculation of heated vapor is effected and the heat is conserved, since the escape of air and vapor at the seating rim is very slight, the noticeable effect being a slight pulsating action. Soap suds entering the fan chamber 14 are drained by the sloping diaphragm 11 and escape through the slots 13 into the annular space 9.

The appliance, as constructed herein, is not dependent upon the use of gaskets or tightly fitting joints between the separable parts, as the water itself, is utilized to seal the bottom of the washing chamber from the atmosphere. A substantial depth of water is also obtained in an appliance of this kind and the washing of the goods effectively brought about because the air is caused to rush in from all sides and over a very material area and to agitate the water at many points or all around the circumference of the washing chamber. Then a recession, rolling or back wash takes place in a marked degree with a corresponding cleansing action on the goods. The same operations occur in placing the working unit B' in any kind of an outer liquid receptacle, such as a pail, laundry tray, etc., providing the washing chamber and the capacity of the fan is such that the level of the water surrounding the inner cylinder seated in the outer receptacle will be lowered to the bottom edge of the cylinder to break the seal as herein described.

What I claim, is:

1. A washing appliance, comprising outer and inner members forming a central washing chamber and a chamber encircling said washing chamber, the outer member being adapted to hold a washing fluid, the inner member having a closed top and being formed with an opening adjacent the bottom of the outer member to permit fluid flow between said washing and encircling chambers; means forming a restricted opening to the atmosphere adjacent the top of said outer member; a suction fan for withdrawing air from the washing chamber; and means for operating said fan, the discharge side of said fan being open constantly to the atmosphere within the confines of said encircling chamber.

2. A washing appliance, comprising laterally spaced outer and inner members forming a central chamber and a chamber encircling said central chamber, the outer member being adapted to hold a washing fluid; a cover for said inner member; a perforated diaphragm in said central chamber forming therein a lower washing chamber and an upper chamber; a suction fan mounted in said upper chamber for withdrawing air from the washing chamber; and means for operating said fan, the wall of the inner member having apertures within the confines of the fan cham-

ber to permit fluid flow between said fan and encircling chambers, and the inner member having an opening adjacent the bottom of the outer member to permit fluid flow between 5 said washing and encircling chambers.

3. A washing appliance, comprising an outer receptacle adapted to hold a washing fluid and open in its upper portion to the atmosphere; an open-bottom and closed-top 10 inner receptacle supported by the outer receptacle in spaced relation to the sides and bottom of the latter; a perforated diaphragm in said inner receptacle forming, in combination with the walls of the latter, an upper chamber 15 in said inner receptacle, the lateral wall of said inner receptacle having apertures within the confines of said upper chamber to permit fluid flow between said upper chamber and the upper part of the lateral space between 20 the receptacle; and means extending within the upper chamber for withdrawing air from said inner receptacle below said diaphragm and discharging it into said upper chamber.

4. A washing appliance, comprising an 25 outer receptacle adapted to hold a washing fluid; a removable cover for said receptacle having an open-bottom skirting disposed within said receptacle and spaced from the sides and bottom of the latter, the space between 30 said receptacle and skirting being open to the atmosphere adjacent said cover; a suction fan mounted in the upper part of the chamber formed within said skirting; and means for actuating said fan, the wall of said 35 skirting adjacent the discharge side of the fan having apertures to permit fluid flow between the skirting chamber and the lateral space between the receptacle and skirting.

5. A washing appliance, comprising a cylindrical receptacle adapted to hold a washing fluid; a cover for said receptacle; an annular open-bottom skirting extending downwardly from said cover a substantial distance into receptacle, said skirting being spaced from 45 the wall of said receptacle; and annular diaphragm located in the upper part of the chamber formed within said skirting and arranged transversely to the axis of the latter, said diaphragm forming, in combination with 50 the wall of said skirting and said cover, an upper chamber; and means in said upper chamber for withdrawing air from the lower part of the skirting chamber, the wall of said upper chamber having apertures to permit 55 escape of the air, the upper part of the space between said skirting and the wall of the fluid receptacle being open constantly to the atmosphere.

6. A washing appliance, comprising a 60 liquid receptacle; a container within said receptacle and in spaced relation thereto, said container extending downwardly nearly to the bottom of said receptacle and being open at its lower end and covered at its top; means 65 for mounting said container in said recep-

tacle; a perforated diaphragm located within the upper end of said container and subdividing the latter into a lower washing compartment and an upper fan compartment; a motor mounted upon the top of said container; and a fan actuated by said motor and located in 70 said upper compartment, said container having wall openings above said diaphragm leading into the space between said receptacle and said container, and said space being constantly open to the atmosphere. 75

7. A washing appliance, comprising a cylindrical receptacle adapted to hold a washing liquid; a removable cover therefor having a cylindrical skirting extending downwardly and forming a washing chamber within said receptacle; means for spacing the bottom edge of said cover from the rim of said receptacle, the bottom of said cylindrical skirting being also spaced from the bottom of said 80 receptacle; a motor and a suction fan driven thereby carried by said cover; and means located within the upper part of said skirting forming an air conduit from the washing chamber to the fan, said motor, fan and conduit serving to withdraw air from the washing chamber when said receptacle is partly filled with a washing liquid, the discharge side of said fan being open constantly to the atmosphere. 85

8. A washing appliance, comprising separate and independent receptacles one within the other and in laterally spaced relation, the bottom of the inner receptacle being open, said inner receptacle serving as a washing 100 chamber; means for suspending said inner receptacle above the bottom of the outer receptacle; a cover for said inner receptacle, said cover being formed with a peripheral flange loosely resting upon the upper rim of said outer receptacle; a suction fan in the upper part of said inner receptacle; and means for actuating said fan, the wall of the inner receptacle adjacent the discharge side of said fan having apertures to permit fluid flow between said discharge side and the space between said receptacles. 105

9. A washing unit for a liquid receptacle, comprising a container open at its lower end and formed with a fan chamber interiorly thereof; and a motor mounted upon said container and having a fan in said fan chamber for withdrawing air from said container, the wall of said fan chamber being formed with an opening providing air communication between said container and the fan chamber, said wall also having apertures leading to the atmosphere. 110

10. A portable washing unit for an open-top liquid receptacle, comprising a hollow 115 upright closed-top washing cylinder having an open bottom and provided with a perforated diaphragm transverse to the axis of the cylinder which forms a lower washing chamber and an upper fan chamber, the wall of 120

said fan chamber being formed with openings leading to the atmosphere; a suction fan mounted in said fan chamber for withdrawing air from the lower washing chamber; and a motor for operating said fan and mounted upon said cylinder.

11. A portable washing unit for an open-top liquid receptacle, comprising a hollow upright closed-top washing cylinder having an open bottom and provided with a perforated diaphragm transverse to the axis of the cylinder which forms a lower washing chamber and an upper fan chamber, the wall of said fan chamber being formed with openings leading to the atmosphere; a suction fan mounted in said fan chamber for withdrawing air from said lower washing chamber, said fan discharging toward said openings; a motor for operating said fan and mounted upon said cylinder; and means formed upon said cylinder above said wall openings for supporting the cylinder within a liquid receptacle.

12. A portable washing unit for an open-top liquid receptacle, comprising a hollow upright closed-top washing cylinder having an open bottom and provided with a perforated diaphragm transverse to the axis of the cylinder which forms a lower washing chamber and an upper fan chamber, the wall of said fan chamber being formed with openings leading to the atmosphere; a suction fan mounted in said fan chamber for withdrawing air from the lower washing chamber, said fan discharging towards said openings; and a motor for operating said fan and mounted upon said cylinder.

In testimony whereof I affix my signature.
PERCY E. BARKER.
